UNITED STATES PATENT OFFICE.

SILAS M. FORD, OF ST. PAUL, MINNESOTA; FINAL DECREE OF COURT ASSIGNS TO CLARA P. FORD, WIDOW OF SAID SILAS M. FORD, DECEASED.

LATH BOARD.

Application filed November 27, 1922. Serial No. 603,656.

One object of my invention is to provide in a lath board means for retaining the board in the shape and size in which it is manufactured.

5 Another object is to provide in a lath board having alternate lath like faces and intermediate depressions, a construction such that a minimum amount of material is required in its manufacture.

10 Another object is to provide in an article of the class described a plurality of lath like faces on one side thereof and a plurality of wide intermediate depressions on the other side thereof.

15 Another object is to provide a binding wire or ribbon of such shape that it can readily be bent to clamp the completed board in its proper shape.

With these and incidental objects in view, 20 the invention consists of certain novel features of construction and combinations of parts, the essential elements of which are hereinafter described with reference to the drawing which accompanies and forms a 25 part of this specification.

In the drawing, Figure 1 is a perspective view of the completed lath board embodying my invention; Figure 2 is an end view of the same; Figure 3 is a perspective view 30 of one of the reinforcing wires before the spearhead end has been bent or formed over, and Figure 4 is a similar view after the spearhead end has been formed into its permanent position.

35 This invention constitutes an improvement of the material produced by the method shown in my Patent No 1,208,535 issued December 12, 1916, and entitled, "Method of making lath board," although following 40 the same general line of producing a lath board of plaited felt or paper having substantially dovetail corrugations therein.

As shown in the drawing, the lath like faces 1 are of width similar to that used 45 in ordinary lath and the depressions 2 intermediate of these lath-like faces are similar to the spaces ordinarily used in lathing, my preference being to have the faces $1\frac{1}{2}$ " in width and depressions $\frac{1}{2}$ " in width.

50 However, instead of having the rear faces 3 of a width equal to that of the front face 1 and as shown in my prior patent, I make these faces narrower, preferably about $\frac{3}{4}$ of an inch and thereby effect a material sav-

ing in the sheet of felt or paper required for 55 forming the completed board.

I also make a material saving in the amount of plaster required to fill the intermediate depressions.

Moreover, as the angles 4 are less with this 60 construction than where both front and rear faces are of equal width, the completed lath board is stronger.

It is evident that with a lath board of this 65 construction there is a tendency for the completed board to "grow", that is the spaces will tend to become wider and the board thicker and hence the overall length of the board greater.

To prevent this, as well as to reinforce 70 the board as described in my prior patent, I use a plurality of reinforcing wires 5, one end of which is bent up as at 6, Figures 3 and 4 and the other end of which is formed into a spearhead 7.

The spearhead has a point 8 which serves 75 to readily pierce the webs 9 of the lath board and has a narrow throat 10 so that where pressure is applied transversely against the spearhead the bend will always be formed at the throat end as shown in Figure 4.

I prefer to insert these wires when the 80 lath board is corrugated and preferably when it is still in the machine which does the corrugating and bend the spearhead over 85 as shown while the board is still in the machine so it is securely held in the shape to which it is formed in the corrugating machine.

While I may make lath board of any size, 90 I find that sheets having a width A of $32\frac{1}{2}$ " and a length B of $25\frac{3}{8}$ " is most convenient for manufacturing and applying to studding in building construction, and in such a sheet I prefer to use seven reinforcing wires uniformly spaced as shown.

95 While I have described my invention and illustrated it in one particular design, I do not wish it to be understood that I limit myself to this construction as it is evident 100 the application of the invention may be varied in many ways within the scope of the following claims.

I claim:

105 1. A board comprising the combination with a sheet of suitable material corrugated to form a plurality of lath-like faces and intermediate depressions, of a reinforcing

wire having each end thereof formed at an angle to the intermediate portion of the wire to maintain the width of the completed board.

5. 2. In a lath board, the combination with a sheet of suitable material having dovetail shaped plaits therein with lath-like faces of a given width on one side thereof and faces of a lesser width on the other side thereof, of webs connecting said faces and a plurality of reinforcing wires piercing said webs intermediate of said faces and having each end thereof formed at an angle to the intermediate portion of the wire to maintain the length of the completed board.

6. 3. A reinforcing wire for lath board having one end thereof formed at substantially

right angles to the length of the wire and having the other end thereof formed into a head with a reduced cross section to locate the bend resulting from transverse pressure on the head.

7. 4. The combination with a sheet of suitable material formed into dove-tailed shape and having substantially opposed faces with connecting webs therebetween, of a wire piercing said webs, one end of said wire being formed over at substantially right angles to the length of said wire, the other end of said wire having a reduced cross section to locate the bend formed by transverse pressure applied at said latter end.

SILAS M. FORD.
